(57) **CLAIM**

The ornamental design for a roof light for vehicle, as shown.

DESCRIPTION

FIG. 1 is a perspective view of the top surface of the roof light for vehicle;

FIG. 2 is a perspective view of the bottom surface of the roof light for vehicle;

FIG. 3 is a front elevation view of the roof light for vehicle;

FIG. 4 is a front elevation view of the roof light for vehicle;

FIG. 5 is side elevation views of the opposing ends of the roof light for vehicle;

FIG. 6 is a top plan view of the roof light for vehicle; and, FIG. 7 is a bottom plan view of the roof light for vehicle. The structural elements shown with section lines in FIGS. 1-4, 6, and 7 are provided to indicate that the roof light for vehicle is modular.

The structural elements shown in dotted lines in the Figures indicate elements that form no part of the claimed invention.

1 Claim, 6 Drawing Sheets

FIG. 3

FIG. 4

FIG. 5

FIG. 6

FIG. 7
